UNITED STATES PATENT OFFICE.

JACKSON L. KAIL, OF CHICAGO, ILLINOIS, ASSIGNOR TO THE WINSLOW BROS. CO., OF CHICAGO, ILLINOIS, A CORPORATION OF ILLINOIS.

DOOR-OPERATING MECHANISM FOR ELEVATORS.

SPECIFICATION forming part of Letters Patent No. 699,329, dated May 6, 1902

Application filed October 19, 1901. Serial No. 79,210. (No model.)

To all whom it may concern:

Be it known that I, JACKSON L. KAIL, a citizen of the United States of America, residing at Chicago, in the county of Cook and State 5 of Illinois, have invented certain new and useful Improvements in Door-Operating Mechanism for Elevators, of which the following is a specification.

My invention relates to certain improvements in door-operating mechanism for elevators, the object being to gain simplicity of construction and efficiency in operation; and to such end the invention consists in certain novel features of construction, a description 15 of which will be found in the following specification and the essential characteristics more definitely pointed out in the claims.

In the drawings furnished herewith, Figure 1 is a front elevation of a portion of an 20 elevator-inclosure and a door with my improved mechanism applied thereto. Fig. 2 is a view partly in end elevation and partly in vertical cross-section, the line of section being indicated at 2 2 in Fig. 1. Fig. 3 is a view 25 partly in plan and partly in horizontal section, the line of section being indicated at 3 3 in Figs. 1, 2, and 4. Fig. 4 is an enlarged view of the operating mechanism seen in Fig. 1. Fig. 5 is a vertical longitudinal section in 30 the line 5 5 of Figs. 3 and 6. Fig. 6 is a view partly in end elevation and partly in vertical cross-section, the line of section being indicated at 6 6 in Fig. 1. Fig. 7 is a front view 35 of a portion of a bar with the parts in front cut away in the line 7 7 in Figs. 9 and 10. Fig. 8 is a longitudinal section in line 8 8 of Fig. 10. Fig. 9 is a cross-section in line 9 9 of Fig. 8. Fig. 10 is a horizontal section in line 10 10 of Fig. 8, and Fig. 11 is a perspective view of a sleeve used in the device.

Referring first to Fig. 1, which shows a portion of an ordinary elevator-inclosure, A A' A² are three uprights thereof, connected by a transom A³. Upon the frame thus formed 45 may be supported an inclosing wall of ornamental pattern, leaving an opening a to be closed by the door B. Said door is supported by hangers b b', running upon a track a', secured upon the uprights A A' A² in the ordinary manner.

Adjacent to the upright A' extends a ver-

tical shaft C, suitably supported and continuously rotating in one direction. This shaft may extend from top to bottom of the building and operate all of the elevator-doors located adjacent thereto.

The operating mechanism is contained in a preferably rectangular frame D, one end of which is supported upon the shaft C by a collar c and held in proper relation with the door by a brace d, extending to a bracket d'. The bracket d' is supported by the upright A' and has an arm d² encircling the shaft C to form a bearing therefor at each floor. The frame D has bearing-hubs d³ d⁴, encircling the shaft, 65 the hub d⁴ resting upon the collar c. Within the frame D two beveled gears E F are loosely mounted upon the shaft C, both meshing with the beveled gear G, fast upon a shaft g. Said shaft extends through a worm-gear H and 70 bears without the same a washer h and nuts h' h² upon its reduced end h³. A spring h⁴ encircles the shaft g and is confined between the washer h and the end of the worm-gear H, thereby drawing the beveled pinion G upon 75 the head h⁵ of the worm-gear to create sufficient friction between them to cause the worm-gear to rotate with the gear G. The ends of the worm-gear are reduced, as seen at h⁶ h⁷, and journaled in openings d⁷ d⁸, 80 formed, respectively, in a cross-piece d⁵ and end piece d⁶ of the frame D, and the head h⁵ is secured to the worm by screws h⁸.

A lever I is pivoted to the frame D at i and is provided with a projection I' at its upper 85 end for engagement with a shoe or other suitable mechanism upon the elevator-car for actuating said lever to throw the mechanism into gear and open the door. Said lever has two arms i' i², Fig. 10, connected by screws 90 i³ i⁴ to a split collar K, which works between two flanges m m' upon a sleeve M, Figs. 9 and 11, to raise or lower said sleeve by the action of the lever I. Said sleeve M is cut away at m⁴, Fig. 11, to receive a strut N, secured to 95 the shaft C and bearing against the gears E and F. The sleeve is free to move vertically upon the shaft, but is carried around with the shaft by the strut N and alternately connected to the gears E and F to close or open 100 the door. The sleeve is formed with clutch-teeth m² m³, adapted to engage, respectively,

sockets *e f* in the gears *E F*, Figs. 8 and 9, and said engagement is effected through the oscillation of the lever *I*. The sleeve is normally held out of engagement with either of the gears when the door is closed. A spring *O* is confined between the lever *I* and the arm *d*² of the bracket *d*', the tension of said spring being to crowd the sleeve upward into engagement with the gear *E* and said movement of the lever being limited by a stop *p* upon a bar *P*, Figs. 7 and 9, when the door is closed. The arm *i*² of the lever has two laterally-extending fingers *i*⁵ *i*⁶, one above and one below the bar *P*, the finger *i*⁵ being adapted to be engaged by a stop *p*', similar to the stop *p*, but on the upper side of the bar, and the finger *i*⁶ by the stop *p* to throw the sleeve out of engagement with the gears *E F*. The bar *P* is supported upon the door *B* by brackets *b*² *b*³ *b*⁴ and engages the worm-gear *H* by means of pins *p*², Fig. 3, said pins being arranged in pairs and meshing with the worm-gear. It is readily understood that the rotation of the worm-gear moves the door either into an open or closed position, depending upon the direction of rotation of the worm.

Fig. 1 shows the door in a position intermediate between a closed and open position and in the act of closing, the spring *O* holding the sleeve *M* in engagement with the gear *E*. The direction of rotation of the shaft *C* is shown by the arrows, and because of the engagement of the shaft with the bevel-gear *E* the worm is rotated in the direction indicated by the arrow and the door closed. If, however, the lever *I* is moved in the opposite direction, the gear *F* is thrown into engagement with the shaft, the worm rotated in the opposite direction, and the door opened. When the door reaches either of its extreme positions, the clutch is moved into its neutral position by engagement of one of the two stops *p p'* with the lever *I*.

I claim as new and desire to secure by Letters Patent—

1. In a door-operating mechanism, the combination with a suitable support, of a slidable door, a bar thereon having a series of laterally-extending pins, a worm parallel with said bar and in engagement with said pins and means for imparting rotation to said worm alternately in opposite directions; substantially as described.

2. The combination with a slidable door and devices for opening and closing the same, of a spring-pressed frictional connection interposed in said devices whereby the tension of the spring fixes and limits the pull on the door; substantially as described.

3. In combination, a rotatable shaft, a door, a bar upon said door, a worm-gear in mesh with said bar, a beveled gear frictionally connected with said worm, gears meshing with

said beveled gear upon opposite sides of its diameter and each adapted to be thrown into engagement with the shaft; substantially as described.

4. In combination, a rotatable shaft, a door, a bar upon said door, a worm-gear meshing with said bar, a beveled gear held in frictional contact with said worm-gear, gears meshing with said beveled gear upon opposite sides thereof and means for throwing either of said gears into engagement with the shaft; substantially as described.

5. In combination, a rotatable shaft, a door, a worm-gear adapted by its rotation to operate said door, a beveled gear frictionally connected to the worm-gear, gears loose upon said shaft and meshing with said first-named gear upon opposite sides thereof, a sleeve non-rotatable with respect to the shaft but capable of longitudinal movement thereon, and adapted to connect either of said second-named gears to the shaft; substantially as described.

6. In combination, a rotatable shaft, a door, a bar supported thereon, a worm-gear meshing with said bar, and adapted to be thrown into or out of gear with the rotatable shaft and stops adapted to automatically throw said worm out of gear with the shaft when the door reaches its open or closed position; substantially as described.

7. In combination, a rotatable shaft, a door, a bar supported thereon, a worm-gear, gearing between said worm-gear and the rotatable shaft, a lever for throwing said worm-gear into or out of gear with the shaft, and stops upon the bar adapted to engage the said lever when the door reaches its open or closed position and automatically throw the worm-gear out of engagement with the shaft; substantially as described.

8. The combination of a door, a rotatable shaft, a supporting-frame, a worm-gear journaled therein, a beveled gear, a shaft carrying said beveled gear and journaled in the worm, a spring adapted to hold the worm-gear and beveled gear in frictional contact, beveled gears loose upon the first-named shaft and meshing with the first-named beveled gear, means for throwing either of said second-named beveled gears into engagement with the shaft, and a device on the door for engagement with the worm; substantially as described.

In witness whereof I have hereunto set my hand, at Chicago, in the county of Cook and State of Illinois, this 19th day of July, A. D. 1901.

JACKSON L. KAIL.
